GRINDING METHOD AND MACHINE

John C. Wilson, Springfield, Ohio, assignor to
The Thompson Grinder Company, Springfield,
Ohio, a corporation of Ohio

Application June 29, 1945, Serial No. 602,275

24 Claims. (Cl. 51—5)

1

This invention relates to a method and apparatus for grinding workpieces and is particularly directed to a grinding method employing a crushing type dresser.

In the grinding of workpieces having complex contours or contours which must be reproduced to a high degree of precision, it has been found that a most satisfactory way of forming the grinding wheel is by crushing it against a formed steel roller which has a cross-sectional configuration identical with that desired to reproduce in the workpieces.

As the wheel is crushed against the dressing roll, the latter gradually wears off until, when the wear exceeds the tolerance limits, it must be replaced with a properly shaped roll. Heretofore, it has been customary for the manufacturer of the grinding machine to supply the rolls with which the purchaser of the machine is to dress the grinding wheel. This involves the shipping of many rolls with its appended hazards and time delays and the necessity of maintaining equivalent standards in two shops, which may be quite remote.

Should the user of the grinding machine desire to shape the rolls in his own plant, it has been necessary heretofore for him to have a cylindrical grinder or its equivalent in order properly to perform this job. Such equipment is very expensive to purchase and maintain.

In either case, it is necessary that the dressing roll be removed from the machine and a new one installed involving a delay period when the grinding machine is out of production.

The principal object of the present invention is to provide a means for overcoming the aforementioned objections so that the grinding machine remains in production substantially continuously.

Another object is to provide a method for truing up a crush dressing roll without removing it from the grinding machine.

Still another object is to provide a grinding machine having a crush dressing roll with a master roll so that the dressing roll may be trued up by the same wheel which it dresses.

Still another object is to provide control means for feeding the wheel and rolls together in order to obtain the best possible dressing result.

The objects of this invention are attained by mounting on a grinder table a master roll of the same configuration as the dressing roll. In operation the wheel is dressed against the dressing roll as often as is desired to maintain the wheel in good condition until the dressing roll has been

2

worn down to one of the tolerance limits. Thereafter, a grinding wheel is dressed by presenting it to the master roll in order to restore the true configuration thereto. Then, the wheel is brought into grinding engagement with the crushing roll while the latter is rotated so that the said configuration is transferred to the dressing roll thus restoring it to its original condition. With the crushing roll trued up it is possible to use it again for dressing the wheel.

The intermittent use of the master roll gives it long life so that a setup including a master roll and a crushing roll will maintain a grinding machine in operation over a period of time which is several times that which could be obtained if the machine were supplied only with a dressing roll. Furthermore, the limits of accuracy may be maintained at a much higher degree than is possible with a single dressing roll.

20 The above objects and further objects and advantages of this invention will be more apparent upon reference to the attached drawings, in which:

Figure 1 is a perspective view of a grinding machine having a production dressing roll and a master dressing roll;

Figures 2 to 10, inclusive, are diagrammatic views illustrating a typical work cycle involving both of the dressing rolls;

Figure 11 is a sectional view taken substantially along the line of 11—11 in Figure 1 illustrating a portion of the mechanism for automatically elevating and lowering the grinding wheel;

Figure 12 is a view taken along the line 12—12 of Figure 11;

Figure 13 is a plan view showing one arrangement of adjustable stop and limit switch for controlling the down-feed of the grinding wheel;

Figure 14 is a plan view over a typical arrangement for supporting and driving a dressing roll;

Figure 15 is a side elevation of a somewhat modified arrangement for adjustably supporting a dressing roll;

Figure 16 is a diagrammatic perspective view illustrating a modified arrangement for dressing the grinding wheel and crushing roll during dressing;

Figure 17 is a sectional view taken on the line 17—17 of Figure 16 illustrating an over-running clutch associated therewith; and

Figure 18 is a wiring diagram adapted for controlling the dressing cycle in any one of the modifications.

Referring to the drawings, there is illustrated in Figure 1 a grinding machine which has a

bed 10 on which is reciprocable a table 12 by motor means which are not shown but which are preferably fluid operable. Suitable controls may be supplied with the motor means for regulating the speed and direction of travel of the table on the bed.

Secured to the bed or fixedly mounted adjacent thereto is a column 14 which slidably supports a saddle 16 on ways which precisely guide said saddle in a vertical direction. Horizontally slidably in the saddle 16 on the ways 18 is a wheel support structure 20 which carries the grinding wheel 22 and its driving motor. The drive shaft of the wheel 22 is mounted in precision bearings for accurately controlling the rotation of the said wheel.

Mounted on the bed 12 is a workpiece holding fixture 24 which may comprise a magnetic plate or any other suitable means for rigidly and accurately securing a workpiece 26 for being operated by the wheel 22.

Mounted at the right end of the table 12 is a unit generally designated 28 which comprises a drive motor 30 and suitable means for rotatably supporting a production dressing roll 32. The unit 28 is more particularly shown in Figure 14 wherein it will be seen to comprise a bed 34 which supports a motor 30 at one end thereof and the roll 32 at the other end thereof. The roll 32 is journaled in heavy duty, precision antifriction bearings such as the ball bearings indicated at 36. Driving means such as the pulleys 38 and belts 40 interconnect the output shaft of the drive motor 30 with the shaft 42 which supports the roll 32.

Mounted at the left end of the table 12 is a similar unit which is generally designated 44 and which comprises a master dressing roll indicated at 46. The units 28 and 44 are precisely aligned by any suitable means such as keys or dowels so that each will engage the wheel 22 in exactly the same manner.

The saddle 16 is provided with a nut 48 which is engaged by a lead screw 50 which is journaled in the column 14. Rotation of the lead screw 50 is operable, through the nut 48, to raise and lower the saddle 16. The lower end of the lead screw 50 has a bevel gear thereon which meshes with a bevel gear on the end of a horizontal shaft 52 which extends through the bed 10 and into the housing 54.

The arrangement within the housing 54 is more particularly shown in Figures 11 and 12 wherein it will be seen that the shaft 52 has keyed thereto a clutch member 55 having teeth adapted for engagement with similar teeth on the end of a sleeve 56 which is rotatably mounted on the said shaft. The clutch 55 is adapted for actuation by a pivoted lever 58 which, in turn, is connected to be actuated by the hand lever 59. The clutch 55 is normally engaged and is disengaged when it is desired to drive the shaft 52 by a motor, not shown.

The sleeve 56 has keyed thereto a pair of ratchet wheels 60 and 62 and a hand wheel 64.

Reciprocably mounted in the compartment 54 are a pair of plungers 66 and 68 which comprise opposed working areas and a central rack portion, the latter being adapted for engagement with the toothed sector 70 and the gear 72, respectively. The toothed sector 70 carries the pawls 74 which engage teeth around the periphery of the ratchet wheel 62. The gear 72 has attached thereto a gear 76 which meshes with a gear 78 attached to an arm which carries the

pawls 80 for engagement with teeth around the periphery of the ratchet wheel 60. Reciprocation of the plunger 66 brings about the counterclockwise rotation of the shaft 52 for downfeeding the wheel 22 while reciprocation of the plunger 68 rotates the shaft 52 in the opposite direction for upfeeding the wheel.

In order to control the amount of downfeed obtained with each reciprocation of the plunger 66, there may be provided an adjustable stop screw 82 which abuts the toothed sector 70 at any desired point.

The plungers 66 and 68 have fluid directed to the opposite ends thereof from a fluid source by a valve arrangement, not shown, but which is preferably solenoid operated.

The hand wheel 64 may be actuated by the knob 84 or a vernier setting of the same may be had by means of the knob 86 which drives through a pinion 87 into a circular rack 89 carried by the housing 54. The periphery of the hand wheel is preferably graduated for indicating the exact amount of up and down feed of the wheel.

The hand wheel 64 also mounts an adjustable cam member 90 which is adapted for contacting a plunger 90 which is carried on a bracket 92. The bracket 92 is pivoted at 94 and has at its inner end a projection 93 adapted for actuating the movable portion 95 of the limit switch LS1 when the bracket is tilted by the engagement of the plunger 90 by the cam 90 as the wheel 64 is indexed in the downfeed direction. The stop member or cam 90 may be adjusted around the periphery of the hand wheel by a toothed shoe 96 which is engaged by a pinion 98 rotated by the lever 100, the latter being stopped in various portions of adjustment by suitable plunger means at 102.

In Figure 18 there is illustrated an electrical circuit for controlling the operation of the grinding machine during its crushing and roll grinding cycles. Between the power lines L1 and L2 there is connected a contactor A through the normally closed limit switch LS2, the normally open start button 150 and the normally closed stop button 152. The switch 150 is bypassed by the blades A1 of the contactor A which provide a holding circuit for the coil A.

A second pair of blades A2 of the contactor A are serially connected with the wheel driving motor 154 which is bypassed by the normally closed blades A3 and the adjustable resistor 156.

Also connected between the power lines is a contactor B in series with the normally closed limit switch LS1, the normally closed stop switch 158 and the normally open start switch 160 the latter of which is bypassed by the blades B1.

A second pair of blades B2 of the contactor B are serially connected with the motor 162 which is adjustable in speed by means of a variable resistor 164. Other means of adjusting the speed of the motor will occur to those skilled in the art but, for the sake of simplicity, there has been shown the resistor 164. The motor 162 has a shaft which carries a cam 166 adapted for closing the switch LS3 which is in series with the blades B3 and the solenoid 168. The switch LS3 is intermittently closed by the cam 166 for intermittently energizing the solenoid 168 which, in turn, actuates the valve 169 which is connected to control the supply of pressure fluid to the opposite ends of the downfeed plunger 66.

The contactor B also has the blades B4 which are in series with the drive motor 30 of the dress-

ing attachment between the power lines **L1** and **L2**.

Also between the lines **L1** and **L2** is a solenoid **170** which is in series with a pair of normally open contacts on the limit switch **LS1** and the selector switch **171**. When the selector switch **171** is closed actuation of **LS1** energizes the solenoid **170** to actuate the valve **173** to bring about a supply of pressure fluid to the upfeed plunger **68** to actuate the ratchet wheel **60** and to elevate the wheel.

Operation of preferred embodiment

A complete cycle of operations include truing of the wheel by the master roll **46** and truing of the roll **32** by the wheel **22** is shown in Figures 2 to 10, inclusive.

In Figure 2 the wheel is being driven at grinding speed and is traversing the workpiece **26** carried on the table **12** by the fixture **24**. When it is desired to true the wheel for dressing the production dressing roll, the wheel is elevated and the wheel and rolls are moved relatively to their Figure 3 position. At this time, the limit switch **LS2** is opened by the cam **153** on the table so that the motor **154** is deenergized by the de-energization of the contactor **A**. Contactor **A** has the blades **A3** which close when the contactor is de-energized and which, when closed complete a circuit across the motor **154** through the resistor **156**. The motor **154** is thus dynamically braked to its halted position. Thereafter, the wheel is moved downwardly to its Figure 4 position until it touches the roll **46**. A predetermined pressure between the wheel and roll is established by turning the hand wheel **64** a predetermined amount and the dressing cycle is commenced by closing the switch **160**.

When the switch **160** is closed, the contactor **B** is energized and the motors **162**, **30** and **31** are also energized. The motor **162** drives the cam **166** thereby intermittently to close the limit switch **LS3** to energize the solenoid **168** to feed the wheel **22** into the roll **46**. As the wheel and roll are fed together the pressure of the roll on the wheel breaks or crushes the bonding agent which holds the abrasive particles of the wheel. The result is a sharp wheel which will grind a workpiece to the exact configuration of the roll. When the wheel has been fed down until the limit switch **LS1** opens, the contactor **B** and the motors **162**, **30** and **31** are deenergized bringing the wheel and roll to a halt. The switch **171** being open at this time the wheel does not feed upwardly but remains in contact with the roll **46** under pressure.

Thereafter, the operator elevates the wheel from the roll as shown in Figure 6 either by manually actuating the wheel **64**, or by actuating the lever **59** to disengage the clutch member **55** and to energize the motor to drive the shafting **52** in the proper direction. The operator thus moves the wheel and table relatively to their Figure 7 position to place the wheel under the roll **32**.

The wheel motor **154** is now energized by closing the switch **150** so that the wheel **22** rotates at grinding speed. The operator then closes switch **171**, and also closes switch **160** to energize the contactor **B** to again energize the motors **162**, **30** and **31**. The wheel **22** now feeds down as indicated in Figure 8 and grinds the roll **32** to the proper shape. When the switch **LS1** is again actuated, the contactor **B** is deenergized to halt the motors **162**, **30** and **31** while the solenoid **170** is energized, due to the now closed switch **171**, to

upfeed the wheel from the roll. The upfeeding of the wheel occurs substantially instantaneously so that it precedes the stopping of the roll **32** thereby preventing a flat spot from being ground on the latter.

A new cycle of grinding operations may now be commenced with the wheel being dressed by the production dressing roll **32** until the latter is worn down to the tolerance limits.

There is illustrated in Figure 15 a modified form of support for the rolls which permits the said roll to be vertically positioned in order to bring it to the level of the workpiece being ground so that during ordinary dressing of the wheel the same may be moved directly from the dressing roll to the workpiece with the adjustment of the downfeed stop. In Figure 15 there is a bed **200** and a sub-bed **202** which supports the crusher drive motor **204** and the crusher roll **206**. An eccentric shaft **208** may be actuated to adjust the table **202** about its pivot **210** thereby to elevate or lower the roll **206**.

The roll **206** may be automatically fed into the wheel instead of the wheel being fed into the roll by connecting with the shaft **208** a worm and wheel reduction unit as at **212** which is actuated by the ratchet **214** and the solenoid and pawl arrangement at **216**. By mounting a limit switch **LS1a** on one of the beds and an adjustable plunger **215** on the other of the beds, the crusher roll **206** may be automatically and intermittently fed into the wheel by the circuit of Figure 18, the solenoid **216** in this case replacing the solenoid **168**, and the switch **LS1a** replacing the switch **LS1**.

In the case of very large and heavy wheels it is necessary to drive the wheel directly at crushing speed rather than by the crushing roll. An arrangement of this type is illustrated in Figure 16 wherein the wheel **300** is adapted for being driven at grinding speeds by the motor **302** and at dressing speeds by the motor **304** which is connected through reduction gearing at **306** and an over-running clutch at **308** with the drive shaft of the motor **302**. The dressing roll **310** is rotatably mounted in a frame **312** on the bed **314** of the machine and is driven by the wheel when the latter is in engagement therewith. It will be obvious that this mounting applies only to the master dressing roll while the production dressing roll would be provided with means for driving it in rotation when it was being trued by the grinding wheel.

The over-running clutch at **308** is illustrated in Figure 17 wherein it will be seen to comprise a shell **316** which is secured to the drive shaft of the motor **302** and an inner clutch member **318** which is secured to the output shaft of the motor **304**. The clutch member **318** comprises the inclined surfaces **320** between which and the shell **316** the rollers **322** wedge when the clutch is driven counterclockwise at a greater speed than the shell. When the shell is driven at greater speed than the clutch the rollers are separated from the surfaces **320** and no driving action takes place between the clutch and shell.

It will be understood that various modifications and arrangements in structure could be made without departing from the spirit of my invention and, accordingly, I desire to comprehend such modifications and substitutions of equivalents as may be considered to come within the scope of the appended claims.

I claim:

1. A method of dressing the working surface

of a grinding wheel and a crushing roll operatively associated therewith which comprises the steps of, engaging a crushing roll against the working surface of a grinding wheel to crush form the grinding wheel working surface thereby complementary to that of the surface of crushing roll, establishing a surface-truing roll in position for engagement by the working surface of the grinding wheel with the surface form of the truing roll in radial alignment with the surface form of the crushing roll, and intermittently causing the working surface of the grinding wheel to engage the truing roll to crush form the grinding wheel surface thereby complementary to that of the surface of the truing roll and thence causing the grinding wheel to engage the crushing roll to grind form the surface of the crushing roll thereby to that of the surface of the truing roll.

2. The method of dressing the working surface of a grinding wheel and of a crushing roll in operative association therewith which comprises the steps of, engaging a crushing roll with the working surface of a grinding wheel with the surface form of the crushing roll in radial alignment with complementary surface parts on the grinding wheel to crush form the grinding wheel complementary to that of the surface of the crushing roll, establishing a surface-truing roll in position for engagement by the working surface of the grinding wheel with the surface form of the truing roll in radial alignment with the surface form of the crushing roll and with the complementary surface parts on the grinding wheel, and intermittently causing the grinding wheel surface to engage the truing roll to crush form the grinding wheel surface thereby to that of the truing roll and thence contacting the crushing roll in grinding engagement to grind form the surface of the crushing roll thereby to that of the surface of the truing roll.

3. A method of dressing the working surface of a grinding wheel and a crushing roll operatively associated therewith which comprises the steps of, engaging a crushing roll against the working surface of a grinding wheel and crush forming the grinding wheel working surface thereby complementary to that of the surface of the crushing roll, establishing a surface-truing crushing roll in position for engagement by the working surface of the grinding wheel with the surface form of the truing roll in radial alignment with the surface form of the crushing roll, and intermittently causing the working surface of the grinding wheel to engage the truing roll and crush form the grinding wheel surface thereby complementary to that of the surface of the truing roll and thence causing the grinding wheel to engage the crushing roll and grind form the surface of the crushing roll thereby to that of the surface of the truing roll.

4. A method of dressing the working surface of a grinding wheel and a crushing roll operatively associated therewith which comprises the steps of, engaging a crushing roll against the working surface of a grinding wheel and crush form the grinding wheel working surface thereby complementary to that of the surface of the crushing roll, establishing a surface-truing roll in position for engagement by the working surface of the grinding wheel with the surface form of the truing roll in radial alignment with the surface form of the crushing roll, intermittently causing the working surface of the grinding wheel to engage the truing roll and crush form the grinding wheel surface thereby complementary to that of

the surface of the truing roll and thence causing the grinding wheel to engage the crushing roll and grind form the surface of the crushing roll thereby to that of the surface of the truing roll, and causing all relative movements between said wheel and said rolls to be carried out in coplanar relationship.

5. The method of maintaining accurate the working configuration of a grinding wheel which comprises, establishing first and second crush dressing rolls having like configurations complementary to the configuration they place on a grinding wheel in position for engagement with the working surface of a grinding wheel by relative movement therebetween and in a fixed coplanar position with each other and with corresponding parts of said wheel, crush forming the wheel by one of said rolls to crush dress the surface of the wheel to within predetermined limits, intermittently crush dressing the wheel by the second roll to crush dress the surface of the wheel to within other predetermined limits, and thereafter grinding the said one roll by the wheel as crush dressed by said second roll to re-form the surface of the said one roll to that of the surface form of the second roll.

6. The method of maintaining accurate the working configuration of a grinding wheel which comprises, establishing first and second crush dressing rolls having like configurations complementary to the configuration they place on a grinding wheel in position for engagement with the working surface of a grinding wheel by relative movement therebetween and in a fixed coplanar position with each other and with corresponding parts of said wheel, crush forming the wheel by one of said rolls to crush dress the surface of the wheel thereby so long as the surface of the said one roll remains within predetermined limits of original accuracy, intermittently crush dressing the wheel by the second roll to crush dress the surface of the wheel thereby to restore the wheel to within limits of original accuracy, and thereafter grinding said one roll by the wheel as crush dressed by said second roll to restore the surface of the said one roll to within limits of accuracy of the said second roll.

7. A method of dressing the working surface of a grinding wheel and of a crushing roll in operative association therewith which comprises the steps of, engaging a crushing roll with the working surface of a grinding wheel with the surface of the crushing roll in radial alignment with complementary surface parts on the grinding wheel and causing rotation of the grinding wheel and of the crushing roll at substantially the same peripheral speed while retaining crushing pressure therebetween to surface form the grinding wheel complementary to that of the surface of the crushing roll, establishing a surface-truing roll in position for engagement by the working surface of the grinding wheel with the surface form of the truing roll in radial alignment with the surface form of the crushing roll and with the complementary surface form of the grinding wheel, and intermittently causing the grinding wheel to engage the truing roll with rotation thereof at substantially the same peripheral speed as the truing roll with crushing pressure therebetween to surface form the grinding wheel to that of the surface of the truing roll, and thereafter causing the grinding wheel to engage the crushing roll at grinding speed relative to the crushing roll to reform the surface of the crushing roll to that of the surface of the truing roll.

8. The method of maintaining accurate the working configuration of a grinding wheel which comprises, establishing first and second crush dressing rolls having like configurations complementary to the configuration they place on a grinding wheel in position for engagement with the working surface of a grinding wheel by relative movement therebetween and in a fixed coplanar position with each other and with corresponding parts of said wheel, crush forming the wheel by one of said rolls to crush dress the surface of the wheel thereby so long as the surface of the said one roll remains within predetermined limits of original accuracy, crush dressing the wheel by the second roll after said one roll has been worn beyond predetermined limits of original accuracy while crush dressing the wheel to crush dress the surface of the wheel thereby to within limits of original accuracy of said second roll, and thereafter grinding said one roll by the wheel as crush dressed by said second roll to restore the surface of the said one roll to within limits accuracy of the said second roll.

9. The method of maintaining accurate the working configuration of a grinding wheel which comprises, establishing first and second crush dressing rolls having like configurations complementary to the configuration they place on a grinding wheel in position for engagement with the working surface of a grinding wheel by relative movement therebetween and in a fixed coplanar position with each other and with corresponding parts of said wheel, crush forming the wheel by one of said rolls to crush dress the surface of the wheel thereby so long as the surface of the said one roll remains within predetermined limits of original accuracy, intermittently crush dressing the wheel by the second roll of crush dress the surface of the wheel thereby to restore the wheel to within limits of original accuracy, thereafter grinding said one roll by the wheel as crush dressed by said second roll to restore the surface of the said one roll to within limits of accuracy of the said second roll, and carrying out all relative movements between said wheel and said rolls in coplanar relationship.

10. The method of maintaining accurate the working configuration of a grinding wheel which comprises, establishing first and second crush dressing rolls having like configurations complementary to the configuration they place on a grinding wheel in position for engagement with the working surface of a grinding wheel by relative movement therebetween and in a fixed coplanar position with each other and with corresponding parts of said wheel, crush forming the wheel by one of said rolls to crush dress the surface of the wheel thereby so long as the surface of the said one roll remains within predetermined limits of original accuracy, crush dressing the wheel by the second roll after said one roll has been worn beyond predetermined limits of original accuracy while crush dressing the wheel to crush dress the surface of the wheel thereby to within limits of original accuracy of said second roll, thereafter grinding said one roll by the wheel as crush dressed by said second roll to restore the surface of the said one roll to within limits of accuracy of the said second roll periodically so long as the second roll remains within predetermined limits of accuracy.

11. The method of maintaining accurate the working configuration of a grinding wheel which comprises, establishing first and second crush

dressing rolls having like configurations complementary to the configuration they place on a grinding wheel in position for engagement with the working surface of a grinding wheel by relative movement therebetween and in a fixed coplanar position with each other and with corresponding parts of said wheel, crush forming the wheel by one of said rolls to crush dress the surface of the wheel to within predetermined limits, intermittently crush dressing the wheel by the second roll to crush dress the surface of the wheel to within other predetermined limits, thereafter grinding the said one roll by the wheel as crush dressed by said second roll to re-form the surface of the said one roll to that of the surface form of the second roll, and separating the wheel and said one roll during grinding thereof by said wheel while said wheel and said one roll are rotating.

12. In grinding machine, in combination, a work station adapted to receive a workpiece for grinding, a grinding wheel operably associated with said work station and mounted on the machine for relative movement between said wheel and the work station, drive means connected with said wheel to drive the same at grinding speed, first and second crush forming rolls including mechanism mounting the same on the machine in a fixed coplanar relationship with said grinding wheel, said mounting for said wheel and the mounting means for said rolls providing for relative movement between said rolls and said wheel for engagement of said wheel with either of said rolls selectively and for movement of said wheel into operable association with said work station, and drive means connected with at least one of said rolls to drive the same at a speed substantially less than grinding speed.

13. In a grinding machine, in combination, a work station adapted to receive a workpiece for grinding, a grinding wheel operably associated with said work station and mounted on the machine for relative movement between said wheel and the work station, drive means connected with said wheel to drive the same at grinding speed, first and second crush forming rolls including mechanism mounting the same on the machine in a fixed relationship with said grinding wheel with the form surface of said rolls coplanar with each other and coplanar with the corresponding work surface of the grinding wheel, said mounting for said wheel and the mounting means for said rolls providing for relative movement between said rolls and said wheel for engagement of said wheel with either of said rolls selectively and for movement of said wheel into operable association with said work station, drive means connected with at least one of said rolls to drive the same at a speed substantially less than grinding speed, and control means operably connected with said wheel drive means selectively rendering said wheel drive means operative or inoperative at grinding speed when said wheel is in engagement with the driven roll.

14. In a grinding machine, in combination, a work station adapted to receive a workpiece for grinding, a grinding wheel operably associated with said work station and mounted on the machine for relative movement between said wheel and the work station, drive means connected with said wheel to drive the same at grinding speed, first and second crush forming rolls including mechanism mounting the same on the machine in a fixed relationship with said grinding wheel with the form surface of said rolls coplanar with

each other and coplanar with the corresponding work surface of the grinding wheel, said mounting for said wheel and the mounting means for said rolls providing for relative movement between said rolls and said wheel for engagement of said wheel with either of said rolls selectively and for movement of said wheel into operable association with said work station, drive means connected with at least one of said rolls to drive the same at a speed substantially less than grinding speed, control means operably connected with said wheel drive means selectively rendering said wheel drive means operative or inoperative at grinding speed when said wheel is in engagement with the driven roll, and including control means rendering said wheel drive means inoperative to drive the wheel at grinding speed when said wheel is in engagement with the other of said rolls.

15. In a grinding machine, the combination of, a work station adapted to receive a workpiece for grinding, a grinding wheel operably associated with said work station, first and second crush forming rolls positioned on the machine in operative association with said wheel on axes parallel with the axis of said wheel with their surface forms in fixed coplanar relationship with each other and in fixed coplanar relationship with the corresponding work surface of said wheel, mounting mechanism supporting said wheel and said rolls on the machine for relative movement between the wheel and the rolls selectively and for relative movement between said wheel and the work station, drive mechanism connected with said mounting mechanism for said wheel and rolls for relatively moving said wheel and said rolls into and out of crush forming engagement selectively between said wheel and said rolls, drive means for rotating said wheel and either roll engaged thereby at a speed substantially less than grinding speed while in crush forming engagement whereby to crush form the working surface of the grinding wheel, and drive mechanism connected with said wheel and at least one of said rolls to drive said wheel at grinding speed and the said roll at substantially less than grinding speed with engagement between said grinding wheel and the said one roll to grind form the said roll.

16. In combination in a grinding machine; a grinding wheel; a production crushing roll operable to dress the wheel between first predetermined limits; a master crushing roll operable to dress the wheel between second and closer predetermined limits; independent supporting means mounting said rolls for rotation on axes parallel with the axis of rotation of said wheel, said supporting means also holding said rolls with their corresponding parts co-planar with each other and also with the same parts of said wheel; a first motor for driving the wheel at grinding speed for operating a workpiece or for grinding said production roll; a second motor for driving said wheel at dressing speeds for dressing the wheel by either of said rolls; and control means connected with said wheel and rolls operable automatically to feed the wheel and the roll by which it is being dressed, or which it is grinding, together a predetermined distance.

17. In combination in a grinding machine; a grinding wheel; a table; a production crushing roll operable to dress said wheel between first predetermined limits and mounted on said table; a master crushing roll operable to dress said wheel between limits closer than said predeter-

mined limits and also mounted on said table independently from said production roll; said rolls and wheel having their corresponding parts co-planar in one plane, and the working surfaces of said rolls being co-planar in a plane parallel to and above said table; a first motor for driving the wheel at grinding speed for grinding a workpiece on said table or for grinding said production roll; a second motor for driving said wheel at dressing speeds for dressing the wheel by either of said rolls; and control means connected with said wheel and rolls operable automatically to feed the wheel and the roll by which it is being dressed, or which it is grinding, together a predetermined distance.

18. In a grinding machine, the combination of, a work station adapted to receive a workpiece for grinding, a grinding wheel operably associated with said work station, first and second crush forming rolls positioned on the machine in operative association with said wheel on axes parallel with the axis of said wheel with their surface forms in fixed coplanar relationship with each other and in fixed coplanar relationship with the corresponding work surface of said wheel, mounting mechanism supporting said wheel and said rolls on the machine for relative movement between the wheel and the rolls selectively and for relative movement between said wheel and the work station, drive mechanism connected with said mounting mechanism for said wheel and rolls for relatively moving said wheel and said rolls into and out of crush forming engagement selectively between said wheel and said rolls, drive means for rotating said wheel and either roll engaged thereby at a speed substantially less than grinding speed while in crush forming engagement whereby to crush form the working surface of the grinding wheel, drive mechanism connected with said wheel and at least one of said rolls to drive said wheel at grinding speed and the said roll at substantially less than grinding speed with engagement between said grinding wheel and the said one roll to grind form the said roll, and control mechanism operatively connected with said drive mechanism for said wheel to render the same inoperative to drive said wheel at grinding speed when in engagement with the other of said rolls.

19. In a grinding machine, the combination of, a work station adapted to receive a workpiece for grinding, a grinding wheel operably associated with said work station, first and second crush forming rolls positioned on the machine in operative association with said wheel on axes parallel with the axis of said wheel with their surface forms in fixed coplanar relationship with each other and in fixed coplanar relationship with the corresponding work surface of said wheel, mounting mechanism supporting said wheel and said rolls on the machine for relative movement between the wheel and the rolls selectively and for relative movement between said wheel and the work station, drive mechanism connected with said mounting mechanism for said wheel and rolls for relatively moving said wheel and said rolls into and out of crush forming engagement selectively between said wheel and said rolls, drive means for rotating said wheel and either roll engaged thereby at a speed substantially less than grinding speed while in crush forming engagement whereby to crush form the working surface of the grinding wheel, drive mechanism connected with said wheel and at least one of said rolls to drive said wheel at grinding speed and the

said roll at substantially less than grinding speed with engagement between said grinding wheel and the said one roll to grind form the said roll, and control mechanism operatively connected with said drive mechanisms to render said last-mentioned mechanism inactive and concurrently render said first mechanism active for disengagement of said wheel and rolls.

20. In a grinding machine, the combination of, a work station adapted to receive a workpiece for grinding, a grinding wheel operably associated with said work station, first and second crush forming rolls positioned on the machine in operative association with said wheel on axes parallel with the axis of said wheel with their surface forms in fixed coplanar relationship with each other and in fixed coplanar relationship with the corresponding work surface of said wheel, mounting mechanism supporting said wheel and said rolls on the machine for relative movement between the wheel and the rolls selectively and for relative movement between said wheel and the work station, drive mechanism connected with said mounting mechanism for said wheel and rolls for relatively moving said wheel and said rolls into and out of crush forming engagement selectively between said wheel and said rolls, drive means for rotating said wheel and either roll engaged thereby at a speed substantially less than grinding speed while in crush forming engagement whereby to crush form the working surface of the grinding wheel, drive mechanism connected with said wheel and at least one of said rolls to drive said wheel at grinding speed and the said roll at substantially less than grinding speed with engagement between said grinding wheel and the said one roll to grind form the said roll, and control mechanism actuated by a predetermined movement of said first drive mechanism in moving said wheel into said rolls to render the said mechanism inactive for moving said wheel into the roll engaged thereby.

21. In a grinding machine, the combination of, a work station adapted to receive a workpiece for grinding, a grinding wheel operably associated with said work station, first and second crush forming rolls positioned on the machine in operative association with said wheel on axes parallel with the axis of said wheel with their surface forms in fixed coplanar relationship with each other and in fixed coplanar relationship with the corresponding work surface of said wheel, mounting mechanism supporting said wheel and said rolls on the machine for relative movement between the wheel and the rolls selectively and for relative movement between said wheel and the work station, drive mechanism connected with said mounting mechanism for said wheel and rolls for relatively moving said wheel and said rolls into and out of crush forming engagement selectively between said wheel and said rolls, drive means for rotating said wheel and either roll engaged thereby at a speed substantially less than grinding speed while in crush forming engagement whereby to crush form the working surface of the grinding wheel, drive mechanism connected with said wheel and at least one of said rolls to drive said wheel at grinding speed and the said roll at substantially less than grinding speed with engagement between said grinding wheel and the said one roll to grind form the said roll, means for bringing said wheel against either of said rolls under pressure while the wheel and roll are not rotating; control means selectively operable thereafter for driving

the wheel and roll at the same peripheral speed while automatically feeding the two together a predetermined distance, and for halting the rotation of the two while still together under pressure, and other control means operable to bring the wheel and one of the rolls together while their surfaces move relatively at grinding speed, automatically to feed the wheel and said one roll together a predetermined amount, and to separate the wheel from the said one roll while both are rotating.

22. In a grinding machine, in combination, a grinding wheel mounted for rotation on a horizontal axis, a work receiving table having a work station thereon, means mounting said grinding wheel and said table on said machine for relative movement therebetween, a crush dressing roll at each end of said table beyond opposite ends of the work station, each of said crush dressing rolls including means mounting the same on an axis parallel with the axis of said wheel and in fixed relationship thereto with the surface forms of said rolls coplanar with said wheel in a plane perpendicular to the axis of rotation of said wheel, means for causing relative movement between said wheel and said table whereby to bring said wheel into engagement with either of said rolls selectively in a straight line movement and including means to apply crushing pressure between said wheel and either of said rolls, and driving means operatively connected with said wheel and at least one of said rolls selectively operable for driving said wheel and either of said rolls at less than grinding speed whereby to crush form said wheel by either of said rolls or driving said wheel at grinding speed while concurrently driving one of said rolls at less than grinding speed whereby to grind-form the said roll by said wheel.

23. In a grinding machine, in combination, a grinding wheel mounted for rotation on a horizontal axis, a work receiving table having a work station thereon, means mounting said grinding wheel and said table on said machine for relative movement therebetween, a crush dressing roll at each end of said table beyond opposite ends of the work station, each of said crush dressing rolls including means mounting the same on an axis parallel with the axis of said wheel and in fixed relationship thereto with the surface forms of said rolls coplanar with said wheel in a plane perpendicular to the axis of rotation of said wheel, means for causing relative movement between said wheel and said table whereby to bring said wheel into engagement with either of said rolls selectively and including means to apply crushing pressure between said wheel and either of said rolls, driving means operatively connected with said wheel and at least one of said rolls selectively operable for driving said wheel and either of said rolls at less than grinding speed whereby to crush form said wheel by either of said rolls or driving said wheel at grinding speed while concurrently driving one of said rolls at less than grinding speed whereby to grind-form the said roll by said wheel, and means for adjusting the vertical position of the said last-mentioned ground roll relative to said table to maintain the working surface of the said roll at the same horizontal level as the other of said rolls relative to the work table.

24. In a grinding machine, in combination, a grinding wheel mounted for rotation on a horizontal axis, a work receiving table having a work station thereon, means mounting said grinding wheel and said table on said machine for relative

15

movement therebetween; a crush dressing roll at each end of said table beyond opposite ends of the work station, each of said crush dressing rolls including means mounting the same on an axis parallel with the axis of said wheel and in fixed relationship thereto with the surface forms of said rolls coplanar with said wheel in a plane perpendicular to the axis of rotation of said wheel, means for causing relative movement between said wheel and said table whereby to bring said wheel into engagement with either of said rolls selectively and including means to apply crushing pressure between said wheel and either of said rolls, and driving means operatively connected with said wheel and at least one of said rolls selectively operable for driving said wheel and either of said rolls at less than grinding speed whereby to crush form said wheel by either of said rolls or driving said wheel at grinding speed while concurrently driving one of said rolls at less than grinding speed whereby to grind-form the said roll by said wheel.

JOHN C. WILSON.
